UNITED STATES PATENT OFFICE.

OSCAR LANGE, OF DRESDEN, SAXONY, GERMANY.

LEAF-TURNER.

SPECIFICATION forming part of Letters Patent No. 395,064, dated December 25, 1888.

Application filed April 28, 1888. Serial No. 272,169. (No model.)

To all whom it may concern:

Be it known that I, OSCAR LANGE, a subject of the King of Saxony, residing at the city of Dresden, in the Kingdom of Saxony and German Empire, have invented a new and useful Improvement in Leaf-Turning Apparatus, of which the following is a specification.

My present invention relates to that class of apparatus by which pages of notes and other similarly-detached sheets of paper are turned over as required, and will be fully understood from the annexed drawings and following general description, and subsequently pointed out in the claim.

Figure 1 is a side view of my newly-invented page-turning apparatus. Fig. 2 is a plan view of the same. Fig. 3 is a detail view illustrating a part of the mechanism.

a designates the frame of the apparatus, which is supported by a note-rest.

c designates a shaft secured in the frame *a* by the screw *b'*. Upon this shaft are mounted six revoluble arms, *d*. Each of these arms carries two needles, *e*, which stand at right angles to the said arms and parallel to the plane of the frame *a*.

f designates springs or gum bands, which are attached by one end to the frame *a* and by the other to the shorter ends of the arms *d*.

f' also designates a series of springs fastened to the frame *a* and working upon the longer end of the arm *d*, so that the constant tendency of both the gum bands and the springs is to turn the arms *d* from the right to the left; or, for the same purpose, a spring wound around the shaft *c* and pressing upon the arm *d* may be used, as illustrated by *f*² of Fig. 3. When the arms *d* are turned to the right, they are held in that position in the notches *h* of the plate *i* by the slide *g*. Upon the slide *g* are pins *k*, corresponding to the arms *d*—one pin for each arm. Near the slide *g* is another slide, *l*, held by the spring *m*. Upon this slide *l* is pivoted a bell-crank, *n*, whose motion is controlled by the spring *p*. The slide *l* is attached to a convenient treadle by the cord or wire *o*.

To use this apparatus, the arms *d* are all first folded to the left. Then the lowermost one is folded back to the right into the proper notch of the plate *i* and secured by

the proper pin of the slide *g*. To accomplish this the operator presses down the end *r* of the bell-crank *n* upon the slide *l*, so that the end of the bell-crank will push away the pin *s* and allow the pin *k* to come into place. The last leaf to be turned is now laid on this arm *d* and its needles *e*. The next arm is then brought over and secured in the same way, and the next sheet laid on it, and so on until all have been so placed. When it is desired to turn a leaf, the operator presses down the treadle attached by the cord or wire *o* to the slide *l*, then the end of the bell-crank *n*, engaging one of the pins *k* of the slide *g*, draws it down far enough to release the first arm *d*, which, by the resilience of the gum band *f* and the spring *f'*, will be immediately thrown over to the left, turning over the leaf which it carries with it. When the pressure is removed from the treadle, the spring *m* returns the slide *l* to its original position, and the bell-crank *n*, having returned to its original position by reason of the resilience of the spring *p*, another page may be turned, and so on in the same way until all the pages have been turned.

What I claim as my invention, and desire to secure by Letters Patent, is—

The combination, with the frame *a*, and the shaft *c*, secured thereto, of the arms *d*, mounted upon said shaft *c*, the needles *e*, fastened to said arms *d*, as specified, the rubber bands *f*, attached by one end to the said frame *a* and by the other to the said arms *d*, the spring *f'*, attached by one end to the said frame *a* and acting with the other end upon the arms *d*, the plate *i*, fastened upon said frame *a* and having notches *h*, as specified, the slide *g*, having pins *k*, the slide *l*, moving upon said frame *a* near said slide *g*, the spring *m*, attached to said slide *l* and controlling the motion thereof, the bell-crank *n*, attached to said slide *l*, the spring *p*, attached to said bell-crank *n*, and the cord *o*, attaching the slide *l* to a treadle, all substantially as and for the purpose set forth.

In witness whereof I hereunto set my hand in presence of two witnesses.

OSCAR LANGE.
